ATTY

UNITED STATES PATENT OFFICE

169,442

CLOTHES HANGER OR THE LIKE

Albert I. Israelson, Hartington, Nebr.

Application September 15, 1952, Serial No. 21,464

Term of patent 14 years

(Cl. D80—8)

To all whom it may concern:

Be it known that I, Albert I. Israelson, a citizen of the United States and residing at Hartington, in the county of Cedar, State of Nebraska, have invented a new, original, and ornamental Design for a Clothes Hangers or the like, of which the following is a specification, reference being had to the accompanying drawing, forming part thereof.

In the drawing:

I claim:

The ornamental design for a clothes hanger or the like, substantially as shown.

ALBERT I. ISRAELSON.
